UNITED STATES PATENT OFFICE.

FREDERICK DUDLEY, OF EUGENE CITY, OREGON.

SASH-FASTENER.

SPECIFICATION forming part of Letters Patent No. 283,365, dated August 14, 1883.

Application filed January 30, 1883. (Model.)

To all whom it may concern:

Be it known that I, FREDERICK DUDLEY, a citizen of the United States, residing at Eugene City, in the county of Lane and State of Oregon, have invented certain new and useful Improvements in Window Locks and Stops, of which the following is a specification.

The object of my invention is to provide means for locking the sashes of windows when they are closed, and also to secure them in any desired position when they are partly or entirely opened.

My invention consists in certain peculiarities of construction, to be hereinafter described, and especially in a double bolt and removable key.

In the drawings, Figure 1 shows the window-sash with the lock or stop in the same, the key inserted, and the bolts projecting. Fig. 2 shows the plate to be inserted in the window jamb or frame, with the slots or openings in the same to receive the bolts of the lock. Fig. 3 is a perspective view of the lock detached, and Fig. 4 shows the key.

My invention consists in a window stop or lock provided with two bolts having beveled points or ends, each having an action independent of the other, which are actuated by springs in the lock and retracted by a removable key, so that when the key is withdrawn the window will be secured in the position in which it is placed, whether closed or opened. Said lock is intended to be embedded in the edge of the upright sash-frame, with the bolts projecting to catch automatically in the openings in the metallic plate which is sunk in the window-casing, so that as the sash is raised or lowered the bolts, actuated by the springs of the lock, will catch in the slots or openings in the plate and hold the window at any desired position, and when the key is removed the window will be locked, whether it be raised or lowered, and any change of its position will be impossible without using the key. The beveled ends of the bolts face inward and toward each other, so that it is impossible to spring them out of place.

In the drawings, A is the upright sash-frame, which contains the lock, and B is the plate inserted and secured in the window-frame. It is provided with a series of openings, b, ar-

ranged in pairs and of size just equal to the bolts.

C is the face of the lock, which is arranged flush with the sash-frame A and secured to it by screws, and having two openings in which the bolts move.

D D are the two bolts which project from the face or end of the lock, and are actuated by springs in the usual manner. They are beveled, so that they will readily enter the openings b in the plate B.

E is the key, which, when removed, leaves the window secured, whether closed or partly or entirely opened.

When the key is inserted in the key-hole, if turned up, it will, in the usual manner, retract the upper bolt, and the window may be raised, as the bevel on the lower bolt causes it to slip out of its opening b in the plate B, and the window being raised to the desired elevation, the bolts, actuated by the springs, will engage with the openings in the plate and hold the window at that elevation, and by removing the key the sash is held in that position and cannot be raised or lowered except by the use of the key. If turned down, in like manner the window may be lowered.

In cases where a single beveled bolt is used, any considerable pressure against the beveled edge will cause the bolt to spring back and release the window, and where a single square bolt is used, when the window is raised rapidly, there is danger lest the bolt shall pass the slot or opening in the window-casing; but by the use, as in my device, of two bolts acting independently and having their beveled ends opposite each other, it will be impossible to release the same, as the pressure against one will only bind the other more securely, and as the moment the point reaches the opening in the plate it will begin to enter, it will be impossible to pass by the opening either in raising or lowering.

It will be seen that even if the glass be removed from the sash by a burglar, and his hand inserted, it will be impossible to raise the window when closed, and if partly raised to admit air its position cannot be changed.

This lock may be applied to either the lower or upper sash of a window with the same result.

I am aware that a single bolt actuated by a spring or springs and retracted by a removable key has been hitherto used, and therefore I make no claim to such device or devices, 5 broadly.

I am aware of the Patent No. 253,563, to Tyler and Atwood, and I desire to be understood as disclaiming such device, and I concede the state of the art as found therein; but

10 What I do claim as new and of my invention, and desire to secure by Letters Patent, is—

The combination, in a window or sash lock,

of the two independently-acting bolts D D, actuated by springs within the lock and retracted by the key E, said bolts having their projecting ends beveled in opposite directions, with the metallic plate B inserted and secured in the window-easing, and provided with a series of openings, in pairs, to receive the bolts, 15 and a removable key, all as described. 20

FREDERICK DUDLEY.
